UNITED STATES PATENT OFFICE

166,715

REFRIGERATOR CABINET

Ray C. Sandin, Oak Park, Ill., assignor to Hot-point Inc., a corporation of New York

Application December 30, 1950, Serial No. 13,638

Term of patent 14 years

(Cl. D67—3)

To all whom it may concern:

Be it known that I, Ray C. Sandin, a citizen of the United States, residing at Oak Park, in the county of Cook and State of Illinois, have invented a new, original, and ornamental Design for a Refrigerator Cabinet, of which the following is a specification, reference being had to the accompanying drawing, forming a part thereof.

In the drawing, Fig. 1 is a front perspective view of a refrigerator cabinet showing my new design; Fig. 2 is a side elevation of the door of said refrigerator cabinet; and Fig. 3 is a section of the door taken on line 3—3 of Fig. 1.

The dominant features of the design reside in the portion shown in full lines.

I claim:

The ornamental design for a refrigerator cabinet, substantially as shown and described.

RAY C. SANDIN.
